ATTORNEYS.

UNITED STATES PATENT OFFICE.

EDGAR G. FREILINGER, OF FORT THOMAS, KENTUCKY.

BARREL AGITATOR.

Application filed January 29, 1921. Serial No. 441,063.

To all whom it may concern:

Be it known that I, EDGAR G. FREILINGER, a citizen of the United States, and resident of Fort Thomas, in the county of Campbell and State of Kentucky, have invented certain new and useful Improvements in Barrel Agitators, of which the following is a full, clear, and exact description, reference being had to the drawings forming part 10 of this specification.

My invention relates to agitators for stirring up the material that settles to the bottom of barrels of paint, varnish, and the like, and generally known to the trade as 15 barrel agitators.

In barrel agitators of the past, whatever be the mounting provided for them, or however they may be inserted in the barrel, there are a few defects present which should 20 be avoided. Among these are: ineffectiveness to the agitator itself or location of it at too great a distance from the base of the barrel; tendency of the agitator to rise up in the barrel when being reversed; tendency 25 of the agitator to scrape the base of the barrel or the sides and thus get out of shape itself and deteriorate the barrel; difficulty of mounting the operating rod for the agitator in the barrel without an expensive 30 construction.

The object of my invention is to avoid the various defects in prior structures and generally to provide a construction of agitator which is strong, inexpensive, and 35 efficient for the purposes to which it may be applied and which can be assembled in or removed from the barrel or receptacle without removing the heads or staves of 40 the barrel and without making any holes in the barrel which are not normally present therein.

Among other things I provide an agitator formed of a folded strip of metal which presents upwardly-slanting sides at all portions thereof and a "push button" form of operating rod mounting in the base of the barrel which permits of easy insertion and withdrawal. The strip may be of any type of construction, however, and I do not wish 45 to limit myself to sheet metal parts. My invention consists of that certain novel construction and arrangement of parts to be hereinafter more specifically pointed out and claimed.

In the drawings,

Figure 1 is a vertical sectional view showing the manner of assembling the agitator in the barrel, although some other method could be adopted if desired, or if the size of the agitator required.

Figure 2 is a like view showing the device in use in a barrel.

Figure 3 is an elevation of the operating rod or shaft.

Figure 4 is a perspective view of the device.

Figure 5 is a perspective view of the "snap button" mounting devices.

Figure 6 is a detail section on a larger scale of the agitator central section.

Figure 7 is an end elevation of the agitator.

Figure 8 is a detail of another form of mounting device.

Referring in detail to the drawings, 1 indicates a barrel of usual shape and construction, with heads 2 and 3 and a bung-hole 4. An opening 5 is drilled in the center of the head 2, and also in the base 3 when the part shown in Figure 8 is used.

The bearing 6 consists of a metal casting, stamping or forging having an enlarged central chamber or socket 7, having an opening 8, with a slightly constricted outer margin at 8^a to receive the shaft end and a much smaller opening 9 below to receive a screw 10 by which it is fastened to the inner side of the bottom 3. Otherwise (Figure 8) the bearing may be cast integral with a plug 6^a, which is mounted in a hole in the base of the barrel.

The diameter of the bearing 6 is slightly less than the hole 5 in the head and to secure the bearing in the bottom of the barrel, the casting is passed through the hole 5, the screw 10 being located in place.

Then with a long screw driver, inserted through a pipe or tube, the screw is driven home in the bottom 3. The shaft 11 is preferably rectangular in cross section with a ball 12 at one end, this ball being split as at 13 to give it the necessary resiliency to allow it to be driven through the opening 8 and into the socket 7. The diameter of the ball is such that while force is required to insert it through the opening at 8^a, it will operate freely in the socket 7. While the ball 12 is wholly received in the socket 7, the reduced

portion 14 between it and the rest of the shaft lies in the opening 8.

The agitator 15 is constructed of a wide strip of sheet metal bent longitudinally to form a channeled member, and inverted V-shape in cross section or the bottom may be closed so as to be triangular in section. It is reinforced at the ends by triangular hollow blocks 15^a, mounted within the body and 19 extending below the base thereof and slightly rounded so as to form contact members for the barrel bottom should the agitator tip on the shaft. A V-shaped block 18 preferably hollow and provided with a central 15 sleeve 19 through which passes a rectangular hole 20 to receive the shaft 11 is so fastened or riveted with the center of the blade that the sleeve 19 protrudes from an oblong opening 21 in the top center of the 20 blade. The blade is formed up around the portion 19 and the corners 19^a of this said portion are rounded off to maintain a rounded edge for the agitator throughout and not to interfere with insertion of the same 25 through the bunghole of the barrel.

A threaded cap 22 closes the opening 5 in the barrel when the device is not in use or while shipping. This cap is recessed at 23 to receive the projecting end of the shaft 11 30 so that once it is mounted it does not require removal.

The agitator may be operated by means of a suitable crank fitted to receive the projecting end of shaft 11, or by other mechanical power transmitting devices attached to the shaft. The crank shown has a socket member 11^a of a size to fit the ball of the hole 5 in the barrel and a handle 11^b. The socket 35 guides and steadies the crank when in use. 40 The ball end of the shaft 11 may at any time be inserted through the head-hole and so held that the shaft will pass through it at 20. The shaft is then thrust down until it comes in contact with opening 8 in the bearing 6. 45 Pressure exerted upon the projecting end of shaft 11 will now drive ball 12 through the opening 8 into the central chamber or socket 7 of bearing 6.

It will be noted that the upper end of the 50 socket or bearing member is beveled off as at 21^a and that the central core piece in the agitator blade has a countersunk portion which fits over this beveled portion, thereby permitting the base of the agitator blade to 55 come down very close to the bottom of the barrel.

The fact that the agitating surfaces of the double wall agitator, now described, all face upwardly, the said agitator will always be held down against the bearing or socket at the base of the barrel and when revolved in either direction will force upwardly into the barrel all heavy matter settled to the bottom of the barrel contents. 60 65 The end blocks in the agitator will rub on

the base of the barrel, should tipping take place, thereby saving the agitator and the bottom of the barrel.

The blade may thus be made up cheaply of sheet metal, and the three inexpensive 70 castings within the body of the blade are easily mounted and will not add greatly to the expense. The "snap button" structure of the shaft bearing and shaft end, provides a simple, inexpensive and secure method of 75 mounting the shaft revolvably in the barrel and here again the tendency of the agitator to stay at the bottom of the barrel relieves me of the necessity of providing any complicated or expensive shaft bearing which will 80 prevent accidental jumping of the shaft out of its bearing due to pressure of the agitator during its work.

Having thus described my invention, what I claim as new and desire to secure by Letters Patent, is:—

1. In combination with a barrel having a top and one side hole, a vertical shaft, means in the bottom head of the barrel and on the shaft forming a journal for the shaft, said 90 two means being attachable by thrusting the shaft means into the barrel head means, an agitator blade adapted to be inserted through the side hole, said blade having means for engaging slidably over the shaft, and so formed that it will upon revolution of the shaft be revolved, and upon revolution will tend to force itself downwardly toward the bottom head of the barrel remaining slidably mounted on the shaft. 95

2. In combination with a barrel having a top and one side hole, a vertical shaft, means in the bottom head of the barrel and on the shaft forming a journal for the shaft, said 100 two means being attachable by thrusting the shaft means into the barrel head means, an agitator blade adapted to be inserted through the side hole, said blade having means for engaging slidably over the shaft, and so formed that it will upon revolution of the shaft be revolved, and upon revolution will tend to force itself downwardly toward the bottom head of the barrel, and means on the base of said agitator adapted 105 to take a bearing of limited area on the bottom head of the barrel, upon chance toppling of the said agitator.

3. In combination with a barrel having a top and one side hole, a vertical shaft rectangular in cross section, and adapted to be inserted through the top hole of the barrel, a fitting adapted to receive and hold the lower end of the shaft when thrust against the bottom head of the barrel, an agitator 120 blade formed into the shape of an inverted angle in cross section and adapted to be inserted through the side hole, said agitator having a rectangular hole therein to slidably but nonrotatably engage over the shaft and remain slidably mounted thereon. 125 130

4. In combination with a barrel having a top and one side hole, a vertical shaft rectangular in cross section, and adapted to be inserted through the top hole of the barrel, a fitting adapted to receive and hold the lower end of the shaft when thrust against the bottom head of the barrel, an agitator blade formed into the shape of an inverted angle in cross section and adapted to be inserted through the side hole, said agitator 10 having a rectangular hole therein to slidably but nonrotatably engage over the shaft, and contact blocks arranged at the ends of the agitator blade and extending downwardly therefrom, as and for the purpose described.

EDGAR G. FRELINGER.
